UNITED STATES PATENT OFFICE.

CHARLES T. BRADY, OF DETROIT, MICHIGAN.

DESIGN FOR A DESK UNIT MAGNIFYING LAMP.

Application filed June 9, 1927. Serial No. 22,372. Term of patent 14 years.

To all whom it may concern:

Be it known that I, CHARLES T. BRADY, a citizen of the United States, residing at Detroit, in the county of Wayne and State of Michigan, have invented a new, original, and ornamental Design for Desk Unit Magnifying Lamp, of which the following is a specification, reference being had to the accompanying drawing, forming part thereof.

Figure 1 is a plan view of a desk unit magnifying lamp showing my new design, and Fig. 2 is a side elevation thereof.

I claim:

The ornamental design for a desk unit magnifying lamp, as shown.

CHARLES T. BRADY.
